A. CLELAND

SCREW JACK

Filed Sept. 22, 1921

Inventor

A. Cleland

By

D. Swift

Attorney

UNITED STATES PATENT OFFICE.

ALEX CLELAND, OF NEW ORLEANS, LOUISIANA.

SCREW JACK.

Application filed September 22, 1921. Serial No. 502,407.

To all whom it may concern:

Be it known that I, ALEX CLELAND, a citizen of the United States, residing at New Orleans, in the parish of Orleans, State 5 of Louisiana, have invented a new and useful Screw Jack; and I do hereby declare the following to be a full, clear, and exact description of the invention, such as will enable others skilled in the art to which it 10 appertains to make and use the same.

The invention relates to screw jacks particularly to that kind of jack known as a bottle jack, however the invention may be applied to any kind of jack, said invention 15 having for its object to provide the upper end of the feed screw with an annular ring disposed in a horizontal plane and provided with radially disposed pockets on two levels of said annular ring and having therein a 20 plurality of ball bearings, said ball bearings engaging ball raceways of an annular plate which engages the article being raised or jacked, said annular plate being provided with downwardly and inwardly extending 25 detachable L-shaped lugs, the horizontal arms of which engage under the annular ring and guide the plate in its pivotal action and prevent displacement of the plate.

With the above and other objects in view 30 the invention resides in the combination and arrangement of parts as hereinafter set forth, shown in the drawings, described and claimed, it being understood that changes in the precise embodiment of the 35 invention may be made within the scope of what is claimed without departing from the spirit of the invention.

In the drawings:

Figure 1 is a side elevation of the jack, 40 part of the upper end thereof being broken away to better show the structure.

Figure 2 is a top plan view of the jack part of the article engaging plate being broken away to show the radially disposed 45 pockets for the reception of ball bearings in the annular ring carried by the upper end of the screw.

Referring to the drawings, the numeral 1 designates a casing of a conventional form 50 of bottle jack and 2 the handle carried thereby, by means of which handle the jack may be moved from place to place and positioned as desired. Extending upwardly and slideable in a vertical disposed aperture 3 is a 55 screw 4, said screw being moved upwardly to a conventional form of ratchet mechanism

5. Secured to the upper end of the screw 4 as at 6 is a sleeve 7, said sleeve being provided with radially disposed outwardly and upwardly extending arms 8, which merge 60 into a horizontally disposed annular member. The annular member 9 has an outer level or surface 10 higher than the surface 11 and disposed in said surfaces 10 and 11 and in radial alignment with each other are 65 pockets 10^a and 11^a, in which pockets ball bearings 12 and 13 are disposed. Heretofore considerable difficulty has been experienced during a jacking operation by the binding of the plate which engages an 70 article thereby increasing the power necessary to turn the ratchet mechanism 5. To overcome this difficulty a plate 14 is provided which plate on its under face is provided with ball raceways 15 and 16. The 75 ball raceway 15 receives the balls 12 and the race-way 16 receives the balls 13 thereby providing a double ball bearing article engaging plate for the jack and eliminating the frictional engagement between the article which is being jacked and the jack to a 80 minimum. Secured to the sides of the plate 14 at diametrically opposite points are downwardly extending arms 17, the horizontal portions 18 of which underlie the annular 85 member 9 and prevent the plate 14 from displacement in relation to the annular member 9. The members 17 are detachably secured by means of screws 19 to the plate 14, 90 thereby allowing the plate 14 to be easily 90 and quickly removed for cleaning purposes.

The invention having been set forth what is claimed as new and useful is:

1. The combination with a jack having a 95 movable screw, of an article engaging member carried by said screw, said member comprising a pair of spaced annular members, one of said annular members being provided with radially disposed ball bearings disposed in radially disposed pockets of one of said annular members, the other annular member being provided with raceways engaging said ball bearings.

2. The combination with a jack having a 100 movable screw, of an article engaging member carried by said screw, said article engaging member comprising spaced annular members, one of said annular members being carried by the end of the screw, radially 105 disposed ball bearings disposed in radially disposed pockets on two levels of the screw carried annular members, the second annular 110

member being provided with raceways engaging the balls on both of the levels of the screw carried annular member, diametrically disposed detachable members carried by the upper annular member and extending downwardly and terminating in horizontally disposed arms engaging the under face of the screw carried annular member.

In testimony whereof I have signed my name to this specification in the presence of ¹⁰ two subscribing witnesses.

ALEX CLELAND.
